[57] CLAIM

The ornamental design for attachment to an agricultural implement bean cutter, as shown and described.

DESCRIPTION

FIG. 1 is a front view of a right hand bean cutter for attachment to an agricultural implement showing my new design;

FIG. 2 is a rear view of the bean cutter of FIG. 1;
FIG. 3 is a left side view of the bean cutter of FIG. 1,
the right side being a mirror image of the left side;
FIG. 4 is a top view of the bean cutter of FIG. 1;
FIG. 5 is a bottom view of the bean cutter of FIG. 1;
and

FIG. 6 is a front view of a left hand bean cutter, said left hand bean cutter being a mirror image of said right hand bean cutter.

FIG. 3

FIG. 2

FIG. 1

FIG. 6

FIG. 5

FIG. 4
